UNITED STATES PATENT OFFICE.

WILLIAM J. BOHAN, OF ST. PAUL, MINNESOTA.

LOCOMOTIVE.

1,274,376.

Specification of Letters Patent. Patented Aug. 6, 1918.

Application filed September 15, 1915. Serial No. 50,834.

To all whom it may concern:

Be it known that I, WILLIAM J. BOHAN, a citizen of the United States, residing at St. Paul, in the county of Ramsey and State of Minnesota, have invented certain new and useful Improvements in Locomotives; and I do hereby declare the following to be a full, clear, and exact description of the invention, such as will enable others skilled in the art to which it appertains to make and use the same.

My invention relates to locomotives and has for its object to so improve the same that a maximum load pulling efficiency is obtained, both in respect to the weight of the locomotive and in respect to the fuel consumption.

These objects I attain by a novel co-operative arrangement, with the usual steam cylinders and drive wheels actuated therefrom, of auxiliary motor trucks operated by a generator or dynamo, driven by a steam engine, preferably a steam turbine, which latter is driven from steam generated in the locomotive boiler, and for economy, driven by the exhaust from the locomotive cylinders. This improved locomotive I term "a turbo-electric compound locomotive."

In the preferred embodiment of the invention, the main weight is carried on a multiplicity of drive wheels driven in the customary way from the steam cylinders, but a very considerable part of the weight of the locomotive, to-wit, of the front portion thereof, is carried on a front truck, the wheels of which are driven by electric motors supplied with current from a generator driven by a steam turbine, which, in turn, is driven by the exhaust steam from the locomotive cylinders. Also, the trucks under the tender are driven by electric motors supplied with current from the above noted turbine driven generator. The best practice is to employ a steam turbine to operate the electric generator or dynamo, but it is possible to employ other forms of steam engine for this purpose.

The tender carries a condenser, and the exhaust from the steam turbine is connected to this condenser. From the condenser, the condensed steam or condensate and the circulating water is preferably pumped to and passed over plates of a cooling tower which is also carried by the tender and from which the cool water is delivered back into the water tank of the tender. The feed water to

the boiler is drawn from the condenser at a point where the water is of quite high temperature.

The accompanying drawings illustrate a 60 turbo-electric compound locomotive designed in accordance with my invention. In the said drawings, like characters indicate like parts throughout the several views. Referring to the drawings:

Figures 1 and 1^a are supplemental views in side elevation, partly in diagram and with some parts sectioned, showing a locomotive embodying my invention;

Fig. 2 is a diagrammatic view showing the 70 circuit connections from the dynamo to the several motors.

Of the parts of the locomotive proper, the numeral 1 indicates the boiler, the numeral 2 the cab, the numeral 3 the cylinders, the 75 numeral 4 the main drive wheels, the numeral 6 the feed water pump, the numeral 7 the main steam pipe from boiler to cylinders, and the numerals 8, 9 and 9^a, respectively, the frame, the front wheels and axles 80 of the front truck which carries a very considerable part of the weight of the front part of the locomotive boiler. The truck frame 8 carries electric motors 10 that are geared to the axles 9 of the said front truck. 85 As shown, the truck frame 8 is connected to the front heads of the cylinders 3, by articulate joints 11. The said front truck is, as shown, provided with front or pilot wheels 12 diagrammatically indicated in 90 Fig. 1. The front portion of this said truck carries a "turbo generator set" made up of an electric generator or dynamo 13 and a steam turbine 14, the latter being connected to drive the former, and both being of any 95 suitable well known construction. For instance, the said steam turbine 14 may be of the type known as a low pressure or exhaust steam turbine. The numeral 15 indicates exhaust pipes from the locomotive cylinders 3 100 to the steam turbine 14, and as shown, has a check valve 15^a checking a reverse flow. The exhaust pipe 15 is connected to the locomotive exhaust nozzle 16, by a branch exhaust pipe 17 in which is interposed an 105 over-pressure valve 17^a set to open, say under a pressure of five pounds, so that the surplus exhaust steam in excess of five pounds, will be discharged through the exhaust nozzle. The construction of such 110 valves is well known. The exhaust port of the said steam turbine is connected, by a

long rearwardly extended pipe 18, to a condenser 19, which, as shown, is built into the rear portion of the water tank 20 of the tender 21. This tender 21 is carried on 5 trucks made up of truck frames 22, truck wheels 23 and axles 24. The truck frames 24 carry electric motors 25 that are geared to the axles 24 so that the said motors drive the wheels 23 and cause them to act as 10 auxiliary traction wheels. Between the engine and the tender, the front and rear portions of the exhaust pipe 18 are connected by a flexible hose 26.

The chamber in which the condenser 19 is 15 located, is cut off from the main portion of the water tank 20 by a partition 20^a. The main body and the said compartment of the water tank and the compartment containing the said condenser, are connected by a 20 circulating pipe 27, through a circulating pump 28, preferably of the rotary type. A suction pipe 29 extends from the bottom of the condenser 19 to a so-called condensate pump 30, which latter has a discharge pipe 25 31 terminating in a nozzle located in a position to discharge onto the upper tray of a cooling tower 33, from which the condensed water runs back into the main compartment of the water tank 20. A feed water pipe 30 34 extends from the condenser 19 to the feed pump 6, and the customary feed water pipe 35 leads from the said pump to the locomotive boiler. Within the locomotive cab is an 35 electric motor controller for multiple-control of the motors on the engine and tender. This controller and other electric connections are shown diagrammatically in Fig. 2.

The condenser 19 has vertical tubes connecting upper and lower chambers thereof, 40 and the intermediate chamber of the said condenser has an inlet 19^a and an outlet 19^b. Extending from the top of the chamber in which the said condenser is located, is a pipe 32 that terminates in a spring head 32^a 45 located in position to discharge onto the plates of the cooling tower 33. Here it may be noted that the said cooling tower has slightly inclined alternated plates located, one over the other.

50 The steam exhaust pipe 15 receives the exhaust from both cylinders 3, and at a point forward of its check valve 15^a is connected to the delivery end of a long live steam pipe 36, the rear end of which extends through 55 the engine cab, taps the rear end of the boiler above the water level and is provided with a valve 37 within reach of the engineer.

By the above described arrangement, all, or substantially all of the wheels, both of 60 the locomotive and of the tender are utilized as traction wheels; the main drive wheels being operated by steam and the other wheels being operated by electric motors. Thus all, or substantially all of the weight 65 of the locomotive or tender are rendered

available for traction purposes, and furthermore the electric motors give a continuous application of power which is especially important when the engine is running at slow speeds, as when climbing heavy grades. The 70 locomotive is thus made highly efficient for mountain traffic, but is, nevertheless, very efficient for all railway service. A high load pulling efficiency for a given expenditure of fuel is also another highly desired result attained. 75

Under ordinary conditions, and for the sake of economy, the steam turbine which operates the electric generator will be driven from the exhaust from the locomotive cylinders. When, however, a maximum power is required, as in starting a heavy load or in climbing steep grades, live steam may be admitted to the steam turbine, through the pipe 36, when the valve 37 is open. In starting a train, the electric motors of the front truck of the engine will be used, and the electric motors on the trucks of the tender will be "cut in" and used as boosters, after sufficient speed has been acquired to cause 90 the electric generator 14 to supply the required current. 80

Various different arrangements of circuits, switches, and controlling devices, between the electric generator or dynamo 14 95 and the several truck motors, may be employed. However, in Fig. 2, I have diagrammatically illustrated a complete system for this purpose, which, however, need be only briefly described for the purposes of 100 this case.

The generator 14 is preferably of the "compound wound" type. In the said diagrammatic view, Fig. 2, the generator and motors are diagrammatically shown. The 105 various circuits will not, for the purposes of this case, be specifically followed, but are clear from the diagram itself. The said circuit connections include a generator shunt field controller indicated as an entirety by 110 the numeral 38, and a "forward and reverse" reverser indicated as an entirety by the numeral 39. These two devices 38 and 39 are all well known types and are usually embodied in a controller housing which 115 would be located within the engineer's cab. In the arrangement illustrated in the said diagram view, Fig. 2, the shunt field resistance is connected to the corresponding bars of the controller and controls the output of 120 the generator. The engine motors will be "cut in" in starting, and the tender motors will be "cut in" when the engine has acquired a predetermined speed.

In this improved engine, nearly the entire weight of the engine and tender are 125 utilized for traction purposes, and furthermore, the draft strains are distributed throughout the engine. The result of this is that the greatest possible pulling force is 130

obtained in an engine of given weight and the tendency of the wheels to slip, with incident stress on parts, is reduced to a minimum. Also, great economy in the use of fuel is secured. The electric motors which operate this auxiliary power device may, under most conditions, be driven from the exhaust from the engine cylinders. By such arrangement, all, or nearly all, of the wheels of the locomotive, including those of the tender, are utilized as traction wheels. The steam turbine will be arranged to exhaust into the condenser, wherein a partial vacuum of twenty inches vacuum, more or less, will be maintained. Part of the exhaust from the locomotive cylinders, will, under most conditions, be available in producing forced draft by a discharge through the exhaust nozzle of the locomotive; but when found necessary, an auxiliary blast producing device, such as a fan or blower, may be employed. Such a fan or blower of proper capacity, may, however, be driven by force which is very much less than that which is obtained in the steam turbine and electric motors by the use of exhaust in the manner described.

What I claim is:

1. In a locomotive, the combination with a steam cylinder, drive wheels and connections between the same, of a truck associated with said locomotive, an electric motor for driving the wheels of said truck, and an electric generator supplying current to said motor, and itself driven by a force generated in the locomotive boiler.

2. In a locomotive, the combination with the steam cylinders, drive wheels and connections between the same, of a truck associated with said locomotive, an electric motor for driving the wheels of said truck, an electric generator supplying current to said motor, a steam motor for driving said generator, and steam connections from the locomotive boiler to said steam motor.

3. In a locomotive, the combination with the steam cylinders, drive wheels and connections between the same, of a truck supporting a part of the weight of the locomotive, an electric motor for driving the wheels of said truck, an electric generator supplying current to said motor, a steam motor for driving said generator, and steam connections from the locomotive boiler to said steam motor.

4. In a locomotive, the combination with the steam cylinders, drive wheels and connections between the same, of a truck supporting a part of the weight of the locomotive, electric motors for driving the wheels of said truck, an electric generator supplying current to said motors, a steam motor for driving said generator, and steam connections leading from the exhaust from the locomotive cylinders to said steam motor.

5. In a locomotive, the combination with the steam cylinders, drive wheels and driving connections between the same, of a front truck supporting the front end of the boiler, an electric motor for driving the wheels of said truck, an electric generator on said truck for driving said truck wheels, a steam turbine on said truck for driving said generator, and steam connections from the locomotive boiler to said steam turbine.

6. In a locomotive, the combination with the steam cylinders, drive wheels and driving connections between the same, of a truck supporting the front portion of said locomotive, electric motors for driving the wheels of said truck, an electric generator on said truck for supplying current to said motor, and a steam turbine on said truck connected to the exhaust from the engine cylinders.

7. In a locomotive, the combination with the steam cylinders, drive wheels and driving connections between the same, of a truck supporting the front portion of said locomotive, electric motors for driving the wheels of said truck, an electric generator on said truck for supplying current to said motor, a steam turbine on said truck connected to the exhaust from the engine cylinders, and a condenser connected to the exhaust from said steam turbine.

8. In a locomotive, the combination with the steam cylinders, drive wheels and driving connections between the same, of a truck supporting the front portion of said locomotive, electric motors for driving the wheels of said truck, an electric generator on said truck for supplying current to said motor, a steam turbine on said truck connected to the exhaust from the engine cylinders, and a condenser incorporated in the water tank of said locomotive and connected to the exhaust from said steam turbine.

9. In a locomotive, the combination with the steam cylinders, drive wheels and connections between the same, of a truck supporting a part of the weight of the locomotive, electric motors for driving the wheels of said truck, an electric generator supplying current to said motors, a steam motor for driving said generator, steam connections from the locomotive boiler to said steam motor, a condenser incorporated in the water tank of the locomotive, and feed water connections from said condenser to the locomotive boiler.

10. In a locomotive, including a tender having a water tank, the combination with the steam cylinders, drive wheels and driving connections between the same, of a front truck supporting the front end of the locomotive boiler, electric motors applied to drive the wheels of said truck, other electric motors applied to drive the wheels of the tender trucks, an electric generator supplying current to the said several motors, a

steam motor on said front truck for driving said generator, and steam connections between said boiler and said steam motor.

11. In a locomotive, including a tender 5 having a water tank, the combination with the steam cylinders, drive wheels and driving connections between the same, of a front truck supporting the front end of the locomotive, electric motors applied to drive the 10 wheels of said truck, other electric motors applied to drive the wheels of the tender trucks, an electric generator on said front truck supplying current to the said several motors, a steam motor on said front truck 15 for driving said generator, steam connections between said boiler and said steam motor, and a common controller for the several motors, located in the engine cab.

12. In a locomotive, including a tender 20 having a water tank, the combination with the steam cylinders, drive wheels and driving connections between the same, of a front truck supporting the front end of the locomotive boiler, electric motors applied to 25 drive the wheels of said truck, other electric motors applied to drive the wheels of the tender trucks, an electric generator on said front truck supplying current to the said several motors, a steam motor on said 30 front truck for driving said generator, steam connections between said boiler and said steam motor, and a condenser incorporated in the water tank of said tender and connected to the exhaust from said steam motor.

35 13. In a locomotive, including a tender having a water tank, the combination with the steam cylinders, drive wheels and driving connections between the same, of a front truck supporting the front end of the locomotive boiler, electric motors applied to 40 drive the wheels of said truck, other electric motors applied to drive the wheels of the tender trucks, an electric generator on said front truck supplying current to the 45 said several motors, a steam motor on said front truck for driving said generator, steam connections between said boiler and said steam motor, a condenser incorporated in the water tank of said tender and connected 50 to the exhaust from said steam motor, and a feed water connection from said condenser to the locomotive boiler.

14. In a locomotive, the combination with the steam cylinders, drive wheels, and connections between the same, of a truck supporting part of the weight of the locomotive, an electric motor for driving the wheels of said truck, an electric generator supplying current to said motor, a steam motor for 60 driving said generator, steam connections between the locomotive boiler and said steam motor, a condenser carried by the locomotive, and a steam exhaust conduit connecting said steam motor to said condenser.

65 15. In a locomotive, the combination with

the steam cylinders, drive wheels, and connections between the same, of a truck supporting part of the weight of the locomotive, an electric motor for driving the wheels of said truck, an electric generator supplying 70 current to said motor, a steam motor for driving said generator, steam connections between the locomotive boiler and said steam motor, a water tank, a cooling tower and condenser carried by the locomotive tender, 75 an exhaust pipe connecting said steam motor to said condenser, and circulating connections from said condenser and water tank leading to said cooling tower and from said cooling tower back to said water tank. 80

16. In a locomotive having a plurality of traction wheels, the combination with a steam cylinder and connections between the said cylinder and some of said wheels for driving the latter, of a turbine, connections 85 including electric motors between said turbine and others of said wheels for driving the latter, said turbine being actuated by steam generated in the locomotive boiler.

17. In a locomotive having a plurality of traction wheels, the combination with a steam cylinder and a turbine, of connections between said cylinder and some of said wheels, and between the turbine and some of 95 said wheels, and means for supplying steam to both said cylinder and said turbine from the locomotive boiler.

18. In a locomotive having a plurality of traction wheels, the combination with a steam cylinder and connections between said cylinder and some of said traction wheels, for driving such wheels, connections including electric motors for driving others of the said traction wheels, an electric generator carried by said locomotive, having connections for supplying said motors with current to drive the same, and a steam motor carried by said locomotive to drive by steam said generator from said locomotive. 100

19. In a locomotive having a plurality of traction wheels, the combination with a steam cylinder and connections between said steam cylinder and some of said wheels for driving the latter, an electric motor, connections between said motor and others of said 115 wheels for driving the latter, a turbo-generator set for supplying current to said motor, said turbo-generator set being supplied by steam from the locomotive boiler.

20. In a locomotive and its tender, each having traction wheels, the combination with a steam cylinder, connections between said cylinder and some of said wheels for driving the latter, of electric motor drives for others of said wheels, and means deriving their energy from steam generated in the locomotive boiler for actuating said motor drives. 125

21. In a locomotive and its tender, each having a plurality of traction wheels, the combination with a steam cylinder and con- 130

nections between said cylinder and some of the wheels for driving the latter, of electric motors for driving others of said wheels, and means for supplying electricity to said 5 motors, which means derive their energy from steam generated in the locomotive, said means being carried by the locomotive.

22. In a locomotive and its tender having each a plurality of traction wheels, the combination with steam cylinders on the locomotive and driving connections therefrom to some of said wheels, of a turbo-generator set carried by the locomotive and operated by steam from the locomotive boiler, and electric 10 motors connected with others of said wheels and energized by current derived from the turbo-generator set.

23. The combination with a steam locomotive, of an electric generator, motors adapted 15 to be actuated from the generator to supplement the power of the steam locomotive, a turbine for actuating the generator adapted to be driven by steam exhausted from the locomotive, a condenser connected with the 20 exhaust outlet of the turbine, and means for conducting water from said condenser to the locomotive.

24. The combination with a steam locomotive, of an electric generator, motors adapted 25

to be actuated from the generator, a turbine 30 for actuating the generator, means for conducting steam exhausted from the steam locomotive to the turbine, a condenser connected with the exhaust outlet of the turbine, means for conducting heated water 35 from the condenser to the boiler of the steam locomotive, a cooling tower, means for conveying water from the condenser to the cooling tower, and a storage tank or reservoir for water for the boiler of the locomotive 40 connected with said tower to receive cooled water therefrom.

25. In a locomotive having a plurality of traction wheels, the combination with a steam cylinder and connections between said 45 cylinder and some of said wheels for driving the latter, of an electric motor carried by the locomotive, connections between said motor and other of said wheels for driving the latter, and a steam motor supplied by steam 50 from the locomotive, for generating current to supply said electric motor.

In testimony whereof I affix my signature in presence of two witnesses.

WILLIAM J. BOHAN.
